A. KELSEY.

Hot-Air Furnace.

No. 8,908.

Patented April 27, 1852.

UNITED STATES PATENT OFFICE.

ALEXR. KELSEY, OF ROCHESTER, NEW YORK, ASSIGNOR TO JAMES COWLES.

WARM-AIR FURNACE.

Specification of Letters Patent No. 8,908, dated April 27, 1852.

To all whom it may concern:

Be it known that I, ALEXANDER KELSEY, of Rochester, in the county of Monroe and State of New York, have invented certain new and useful Improvements in Warm-Air Furnaces; and I do hereby declare that the following is a full, clear, and exact description of the same, reference being had to the accompanying drawings, forming part of this specification, in which—

Figure 1, is a front view in elevation. Fig. 2, is a vertical section taken at the line α — α in Fig. 5. Fig. 3, is a side view of the fire pot showing the expansion rod and lever for opening the valve at the bottom of the smoke pipe. Fig. 4, is a section of the smoke pipe showing the self regulating damper. Fig. 5, is a horizontal section taken at about the line Y , Y , Fig. 2. Fig. 6 is a plan or birdseye view of the annular evaporating pan.

Similar letters of reference indicate corresponding parts in each of the several figures.

The nature of my invention consists in the employment of an equalizing flange so arranged that the air which enters the furnace on both sides of a radiating cylinder is warmed to about the same temperature before entering the warm air conducting flues.

To enable others skilled in the art to make and use my invention I will proceed to describe the manner in which it is constructed.

A, Figs. 2, 3, 5 is the fire pot constructed of cast iron. B, is the ash pit. C, is a circular passage around the ash pit, and D, is a tube leading from it to the bottom of the smoke pipe.

E, E, Fig. 2, is a sheet iron cylinder termed a heater. This encompasses the fire pot A, and fits tightly over the top of the base α , or that part which forms the circular passage. d , are openings in the top of the base by which communication is effected between the interior of the heater E, E, tube D, and smoke pipe—the heater E, E, is larger in diameter than the fire pot A, and extends some distance above it and is closed at the top, see Fig. 2.

F, F, is a middle or radiating flue also constructed of sheet iron and surrounding the inner cylinder or heater E, E, a suitable space being between them, this radiating cylinder is open at the top and is nearly as high as the inner cylinder or heater E, E, the lower part fits tightly over

a small vertical projection e , of the base, see Fig. 3.

G, G, is the outer cylinder which incloses the whole, this may be constructed of sheet iron, tin, zinc, or galvanized iron, a suitable space is allowed between the outer and radiating cylinders see Fig. 2. The space between the outer cylinder G, G, and the inner cylinder or heater E, E, is the air chamber 65 and it is divided perpendicularly by the radiating cylinder F, F.

H, H, is an equalizing flange. This is a circular piece of metal attached to the radiating cylinder F, F, and extending inwardly 70 to the heater or inner cylinder E, E, and outwardly to the outer cylinder G, G, this flange divides the air chamber horizontally.

h , h' , are passages or tubes on the flange, tubes inclining inwardly conduct the air in 75 the space between the outer and radiating cylinders below the flange into the space between the heater and radiating cylinders above the flange, and those inclining outwardly conduct the air in the space between 80 the heater and radiating cylinders below the flange into the space between the outer and radiating cylinders above the flange, the air enters the space between the heater and radiating cylinders through the openings f , 85 in the base see Fig. 5, and the space between the outer and radiating cylinder is supplied with air through openings near the bottom of the cylinder or the outer cylinder may be raised a short distance from the ground 90 or floor. By referring to Fig. 2, it will be seen that the black arrows represent the direction of the air in passing up through both spaces formed by the radiating cylinder and also through the tubes h , h' , on 95 the flange H, H. Now it will be seen that all the air that passes up through the air chamber is brought in contact with the heater or inner cylinder, that which passes up through the apertures f , is in contact 100 with the heater below the flange and is conducted in the space between the radiating and outer cylinders by the tubes h' , on the flange, the air that enters underneath or through apertures near the bottom of the 105 outer cylinder is conducted into the space between the heater and radiating cylinder by the tubes h , thus the air as it enters the conducting flues is heated to about the same temperature, any requisite number of tubes 110 may be on the flange.

I, I, Fig. 6, is an annular evaporating pan

constructed of cast iron and placed on the upper end of the outer cylinder and supplied with water through an opening in the top or cover of the cylinder, this is sufficiently 5 above the heater or inner cylinder so that the water is not warmed enough to produce steam or any unnecessary or unpleasant amount of moisture in the warm air discharging flues.

10 J, J, are immediately over the evaporating pan, and the warm air in entering the flues and consequently passing over the water takes up as much of the vapor as it has an affinity for. Thus the heated air is never 15 surcharged with moisture.

K, is a tube connecting the heater or inner cylinder E, E, with the smoke pipe L. m, is a self regulating damper placed within the tube, its arrangement will be distinctly 20 understood by referring to Fig. 4.

g, is a strip of brass attached to the tube and having one end i, bent outward, the damper is hung upon an iron wire j, passing through at about the center of the strip 25 g, this wire on the outside of the tube K, is bent around so as to catch under the lip i, on the brass strip g, and when in this position the damper is open and there is consequently a direct draft from the fire pot

30 A, to smoke pipe L, as seen by the blue arrows Fig. 2, the damper is to be open when kindling the fire and as the heat increases the brass strip g, expands until the iron wire j, is released from the lip i, and 35 falls by its own gravity into the position shown by the dotted lines and the damper is closed, when in this position the draft is in the direction of the red arrows see Fig. 2, thus the heat and gases of combustion are

40 drawn down all around the fire pot and pass through the apertures d, Figs. 1 and 2, into

the circular passage c, and thence into the smoke pipe L, by this arrangement the heater or inner cylinder E, E, is kept at nearly a uniform temperature. There are 45 additional dampers for regulating the supply of air for combustion and to furnish a draft for the smoke flue L, to carry off the smoke and gases when the other damper is closed, by referring to Fig. 3, this arrangement will readily be understood.

M, is the aperture (open) which supplies air for combustion and

N, (closed) is the aperture which supplies a draft to the smoke flue or pipe L, these 55 apertures are covered by lips O, P, attached to a rod R, having its fulcrum at r.

S, is a brass expansion rod its upper end attached to the outside of the smoke pipe and its lower end attached to a small lever 60 s, now as the rod S, expands the lip O, is forced down and the aperture N, is uncovered while at the same time the lip P, rises and the aperture M, is closed by it. The supply of air for combustion may be 65 introduced from the rear and regulated by the same expansion rod but dispensing with the longer lever.

Having thus described the nature of my 70 invention and the manner in which it is constructed what I claim as new and desire to secure by Letters Patent is—

The use of an equalizing flange H, H, with the tubes h, h', attached by which the air on each side of the radiating cylinder is 75 warmed to about the same temperature before entering the warm air conducting flues.

ALEXANDER KELSEY.
